DESIGN FOR AN AUTOMOBILE VISOR MIRROR

Harry Golden, New York, N. Y.

Application August 31, 1944, Serial No. 115,153

Term of patent 7 years

(Cl. D14—6)

To all whom it may concern:

Be it known that I, Harry Golden, a citizen of the United States, residing at New York, county of New York and State of New York, have invented a new, original, and ornamental Design for Automobile Visor Mirrors, of which the following is a specification, reference being had to the accompanying drawing, forming a part thereof.

Figure 1 is a front elevational view of an automobile visor mirror embodying my new design;

Figure 2 is a rear elevational view thereof;

Figure 3 is an end elevational view thereof.

I claim:

The ornamental design for an automobile visor mirror, as shown.

HARRY GOLDEN,
